UNITED STATES PATENT OFFICE

110,530

DESIGN FOR A COMBINED DUPLEX CABINET AND WASHBASIN

Sewall Billings Vaughn, Cambridge, Mass.

Application November 24, 1937, Serial No. 73,175

Term of patent 14 years

To all whom it may concern:

Be it known that I, Sewall Billings Vaughn, a citizen of the United States residing at Cambridge, in the county of Middlesex and State of Massachusetts, have invented a new, original, and ornamental Design for a Combined Duplex Cabinet and Wash Basin, of which the following is a specification, reference being had to the accompanying drawing forming part thereof.

In the drawing,

Fig. 1 is a front perspective view of a combined duplex cabinet and wash basin showing my new design; and

Fig. 2 is a plan view of the wash basin shown in Fig. 1 with the cabinet, appearing at the upper portion of Fig. 1, removed.

I claim:

The ornamental design for a combined duplex cabinet and wash basin, substantially as shown and described.

SEWALL BILLINGS VAUGHN.
